UNITED STATES PATENT OFFICE.

LADISLAW MEDVECZKY, OF BAKOSHEGY, HUNGARY.

ENVELOPE AND OTHER ARTICLE OF PAPER.

Application filed November 17, 1926, Serial No 148 960, and in Hungary November 21, 1925.

My invention relates to envelopes and other articles of paper having sealing edges, such as wrappers for packets, sealing labels, etc. The object of the invention is to prevent sur-
5 repititious opening or unfastening.

It has been proposed to provide the sealing edges of envelopes with perforations, incisions or indentations with a view to increase the tenacity of adherence and to get visible 10 traces of a surreptitious opening. The insufficient safeness thus obtained is increased to a grade of perfection by the improvement which is my invention and consists in providing the sealing edges with incisions so 15 formed as to result in a plurality of strips entirely separated from the body of the envelope or other article and temporarily cohering to a margin which is left intact outside the incisions but will be removed or severed 20 after the strips resulting from the incisions have been sealed down so that the incised edge sealed down will contain a plurality of strips independent of one another as well as of the body of the envelope or other article. 25 These entirely independent strips, which make the characteristic feature of my invention, afford such a grade of safeness against surreptitious opening as was, hitherto, un-attained.

30 The invention is illustrated, by way of example, in the accompanying drawings in which—

Fig. 1 represents the blank of an envelope made in accordance with the invention;

35 Fig. 2 shows the same blank folded for use and with the closing flap open;

Fig. 3 shows the back of the closed envelope.

The blank as shown in Fig. 1 consists of 40 the central field *a—b—c—d*, the back flap *c—e—f—d* to be folded upon the former, the side flaps *a—g—h—c* and *b—i—k—d*, and the closing flap *l—m—b—a*. In cutting out the blank, or in a subsequent punching operation, I provide the side flaps and the closing flap with incisions so formed as to divide the said flaps, or such portions thereof as will 45 be sealed down, into two sorts of narrow strips 7 and 8 projecting between each other, the side edges 6 of the flaps as well as a longitudinal margin 9 on each flap being left intact. The strips 7 remain integral with the central field, or with the intact body portions of the flaps inside the incisions, while the strips 8 are entirely separated from the body 50 of the envelope, temporarily cohering, how-

ever, to the margin 9 which is connected through the intact side edges 6 with the body of the envelope. In the drawings, the strips 8 separated from the body of the envelope but temporarily held together by the margins 9 are distinguished by shading.

60 Gum is applied to such portions of the back flap as will be covered by the incised portions of the side flaps and the closing flap, respectively, in folding and closing the envelope. Prior to sealing down the side flaps, their margins 9 are turned down to be severed after the strips 7 and 8 have stuck fast. As an article of trade, the envelope carries the 70 turned down margin 9 on the closing flap only, preferably in the width of the incised portion of the closing flap in order to serve as a protective cover for the strips 7 and 8 when they are stroked in closing the envelope. 75

In an attempt to open the closed envelope by loosening or unfastening the strips 7, it is inevitable to loose or unfasten also the independent strips 8 which curl under the influence of the heat and moisture applied or, at least, get out of place so that no effort or precaution can accomplish to get the unfastened spot fastened again without leaving evidence of the misdeed.

80 For the sake of simplicity, I have illustrated the strips as of equal form and length, but the incisions can be made after various designs with undulating or branched strips of different length, always, however, in such a 85 manner that the margin 9 having been severed many narrow strips remain isolated preferably filling in the spaces between other strips which cohere to the body of the envelope.

90 It will be understood that my invention is not limited to envelopes and the same may be equally applied for the safe sealing of packets, boxes or other receptacles, the sealing edges of the covering or, if separate sealing labels are used, the edges of the latter being divided in accordance with my invention into strips such as 7 and 8 inside a margin such as 9 which will be severed after the strips have stuck fast.

100 105 What I claim is—

1. An article of paper consisting of a body portion having sealing incised borders and intact margins outside said incised borders, the incisions being so formed as to separate 110 from said body portion a plurality of strips temporarily connected with one another by

said margins but becoming independent of one another when said margins are cut off.

2. An article of paper consisting of a body portion, divided sealing borders, and intact margins outside the latter, said divided borders comprising a plurality of strips separated from said body portion and temporarily connected with one another by said margins but becoming independent of one another 10 when said margins are cut off.

3. An article of paper comprising a body portion, sealing borders divided into two sets of strips, and intact margins outside said divided borders, said strips cohering 15 one set to said body portion and the other set to said margins, the individual strips of the latter set becoming entirely independent when said margins are cut off.

4. An article of paper comprising a body 20 portion, sealing borders divided into two sets

of strips, and intact margins outside said divided borders, said strips cohering one set to said body portion and the other set to said margins, the individual strips of the latter set becoming entirely independent when 25 said margins are cut off, and the strips of one set filling in the spaces between the strips of the other set.

5. An envelope consisting of a central field, a back flap folded upon said central field, two side flaps having divided edges stuck on said back flap and comprising a plurality of entirely independent strips, and a closing flap provided with incisions inside an intact margin, said incisions forming a plurality of 30 strips cohering to said margin but separated from the other portions of said closing flap.

In testimony whereof I hereunto affix my signature.

LADISLAW MEDVECZKY.
